UNITED STATES PATENT OFFICE

2,494,432

BEDSPRING

Charles J. Elder, Muncie, Ind., assignor to The
Moore Company, Muncie, Ind., a corporation
of Indiana

Application September 1, 1944, Serial No. 552,282

2 Claims. (Cl. 5—247)

1

My invention relates to bed springs, and it is my object to produce an improved bed spring which will be sturdy and durable in construction and which will provide adequate comfort. A further object of my invention is to produce a bed spring which can be simply and economically manufactured.

In carrying out my invention, I employ as the resilient load-supporting elements of the bed spring a multiplicity of torsion springs disposed with their axes horizontal and provided with integral arms one of which is connected to the base frame of the spring. The other ends of the torsion-spring arms are connected to each other and to a border frame by flexible strips of metal.

The accompanying drawings illustrate my invention: Fig. 1 is a plan view of one end of a bed spring; Fig. 2 is a transverse section on the line 2—2 of Fig. 1; Fig. 3 is a plan view of the base frame; Fig. 4 is a vertical section on the line 4—4 of Fig. 1; Fig. 5 is a perspective view of one of the torsion springs; and Fig. 6 is a fragmental plan view illustrating a modified construction.

The spring shown in the drawings comprises a base frame including a border member 10, longitudinally extending spring supports 11, and a central cross-member 12, all conveniently formed of angle iron and secured together at their points of intersection. As shown, there are four of the spring supports 11, but this number may vary if desired.

The supporting members 11 as well as the sides and ends of the border member 10 support resilient load-sustaining elements including torsion springs. The preferred form of spring element which is designated in its entirety by the reference numeral 15, is illustrated in Fig. 5. As there shown, each spring element comprises a single piece of spring wire bent perpendicularly on each side of its midpoint to provide an intermediate leg 16 and two parallel legs 17. Intermediate its length, each of the legs 17 is coiled helically, as indicated at 18, and beyond each helically coiled portion 18 the wire continues to form an arm 19. The end of each arm 19 is turned outwardly and formed to provide a hook 20. At the midpoint of the intermediate leg 16, the material thereof is offset downwardly, as indicated at 21. Each offset 21 has a sufficient vertical extent to project through a flange of the angle iron from which the base-frame members 10 and 11 are formed.

The spring elements 15 are desirably arranged in transverse and longitudinal rows on the base frame as indicated in Figs. 1 and 2, with each side

2

of the border member 10 and each of the supporting members 11 supporting a row of spring elements. Desirably, the elements 15 are disposed so that their arms 19 project outwardly from the longitudinal center line of the assembly.

At each end of the spring assembly I preferably provide a transverse row of spring elements, designated 15a in Fig. 1, such elements being supported from the end of the base frame 10 with their arms 19 extending outwardly of the assembly.

For the purpose of securing the springs 15 and 15a in place on the base frame, the border member 10 and the supporting members 11 are provided with slots 25 at the points where they are to support spring elements 15 or 15a, each of such slots being adapted to receive the offset 21 of the associated spring element. In addition to the slots 25 in the horizontal flanges of the border member 10 and supporting members 11, the members 10 and 11 are also provided in their vertical flanges with aligned holes adapted to receive a wire 26. In assembling the bed spring, the offset 21 of each spring element 15 is placed in a slot 25; and after all the springs in each transverse row have been so arranged the wire 26 is inserted passing through the holes in the vertical flanges of the members 10 and 11 and through the offsets 21. The ends of the wire 26 may be bent over to prevent withdrawal of the wire. The spring elements 15a of each end row of such elements are held in place on the adjacent end of the base frame 10 by wire clips 27 shown in Fig. 4. As will be clear from that figure, each clip 27 embodies an eye 28 which embraces the associated offset 21, while the body of the clip extends through the hole in the vertical flange of the border member 10 and is bent to embrace the lower edge of such flange.

The upper margin of the spring assembly is defined by a border frame 30, preferably in the form of a light sheet-metal angle, across which there extend transverse strips of flexible material 31. Desirably, the strips 31 are not continuous, but are interrupted near the longitudinal center-line of the spring assembly, the interruption in each strip being bridged by a short helical tension spring 32. One pair of the strips 31 is associated with each transverse row of spring elements 15. Such strips overlie the hooks 20 of the spring elements of that row and are provided with separated tongues 33 struck downwardly and adapted to receive the hooks 20. Desirably, there is a strip 31 disposed between each pair of transverse rows of spring elements 15,

such strip being connected to those on opposite sides of it by helical tension springs 34.

The hooks 20 of the spring elements 15a at the ends of the assembly may be secured directly to the ends of the border frame 30. For this purpose, the horizontal flange of the border frame is provided with struck-down, hook-receiving tongues 35, similar to the tongues 33 of the strips 31.

If desired, the bed spring may include one or more stabilizers 40 acting between the border frame 30 and the base frame to oppose horizontal displacement of the former. Such devices need not be described in detail, as several different stabilizers are in common use.

The strips 31 need not be secured directly to the sides of the border frame 30, in the manner indicated in Figs. 1 and 2, but instead may be connected to such border frame by interposed helical tension springs 35, as shown in Fig. 6.

I claim as my invention:

1. In a bed spring, a rigid base frame, a border frame above said base frame, a plurality of flexible strips extending transversely of said border frame, transverse rows of springs arranged beneath said strips, each of said springs having an intermediate portion helically coiled on a horizontal axis and lower and upper arms extending from the ends of said coiled portion and secured respectively to said base frame and to one of said strips, said upper spring arm forming a hook and each of said strips being provided with down-struck tongues embracing the hooks of the associated row of springs.

2. In a bed spring, a rigid base frame, a border frame above said base frame, a plurality of flex-

ible strips extending transversely of said border frame, transverse rows of springs arranged beneath said strips, each of said springs having an intermediate portion helically coiled on a horizontal axis and lower and upper arms extending from the ends of said coiled portion and secured respectively to said base frame and to one of said strips, said springs being arranged in pairs, each pair being formed from a single wire, the middle portion of said wire being provided with a downwardly extending offset, said base frame being provided with an opening receiving said offset, means extending through said offset beneath the base frame, the end portions of said wire constituting the upper arms of the pair of springs, said upper arms being secured to adjacent ones of said transverse strips.

CHARLES J. ELDER.
